BOX COVERING MACHINE

William B. Betts, Binghamton, N. Y.

Application October 27, 1941, Serial No. 416,749

14 Claims. (Cl. 93—54.1)

The present invention relates to box covering machines and particularly to an automatic machine of this type for applying a paper covering to the sides of rectangular paper boxes and folding over the covering at the edges. The novel machine of this invention is adapted to utilize paper covering in continuous lengths as distinguished from covering blanks cut for a selected size and shape of box.

Machines of this nature previously known have required manual assistance in their operation, have been wasteful of paper because requiring pre-cut blanks for each size of box, and have often been slower than the lid-covering machines with which they are used in conjunction.

The principal purpose which this invention attains is the provision of a wholly automatic box covering machine which will have a capacity at least equal to that of its companion lid-covering machine.

A further important object is to provide a machine which will use a continuous strip or roll of covering paper or other material. A related object is to provide a cutting mechanism which will sever the strip stock in predetermined lengths variably controlled by the periphery of the box being covered.

An additional object of importance is satisfied by the novel clamping device which has been provided for grasping the inside corners of boxes supplied to the machine, and releasing the same upon completion of the covering procedure. The utility of this clamping device has been increased by providing special adjustments for the accommodation of boxes of different sizes and proportions.

As a still further principal object it is intended to provide end and side wiping mechanisms for laying the extending marginal portions of the cover strip over the bottom of the box and with a single compound motion inwardly and upwardly to fold the edge portions projecting beyond the top of the box and apply them to the inner sides thereof. More specifically, the invention has for its object, the provision of such wiping instrumentalities which will operate at the top and bottom simultaneously on opposite sides of the box and be adjustable for handling boxes of more than one dimension.

A particular feature of novelty resides in the provision for resilient wipers capable of acting upon boxes of a wide range of lengths without manual adjustment.

Other novel details comprising distinct improvements will be apparent and understood from

reading the following detailed description of a preferred embodiment of the invention in connection with the accompanying drawings, in which

5 Fig. 1 is a front elevation of the complete machine of this invention;

Fig. 2 is an end elevation to a larger scale showing particularly the strip feeding and cutting mechanism;

Fig. 3 illustrates in elevation one of the adjustable clamping devices engaging a box; as seen on the plane indicated 3—3 in Fig. 4;

Fig. 4 represents a vertical section taken on line 4—4 of Fig. 3;

15 Fig. 5 is a fragmentary enlarged section taken along line 5—5 of Fig. 3 and shows the cam operating means for the clamping device;

Fig. 6 is a vertical section along the line 6—6 of Fig. 1 illustrating one of the side wiping devices for the box covering;

20 Fig. 7 shows in plan view the wiping device of Fig. 6;

Fig. 8 illustrates by an enlarged vertical section on line 8—8 of Fig. 6 further details of the 25 wiping device;

Fig. 9 is a partial vertical section at line 9—9 of Fig. 7 showing a further detail of the wiping mechanism;

Fig. 10 is similar to Fig. 9 but illustrates the 30 parts in a different operating position;

Fig. 11 is a section taken on line 11—11 of Fig. 8 showing further the relation of the wiping means to a box and the paper cover which is being applied;

35 Fig. 12 is a vertical section on the line 12—12 of Fig. 1 showing certain features of the driving means for the machine;

Fig. 13, which is a vertical section along line 13—13 of Fig. 12, shows the cam means for operating the clutches which control rotation of the 40 respective box blanks at each station of the machine;

Fig. 14 represents a section on line 14—14 of Fig. 12 viewed in the opposite direction from Fig. 45 13;

Fig. 15 is a vertical section on line 15—15 of Fig. 12 showing the combined cam and gear element;

Fig. 16 represents an end view of the stationary 50 cam disc of Figs. 12, 13, and 14;

Fig. 17 shows by an enlarged transverse section on line 17—17 of Fig. 1 the cam means for extending the box clamping devices; and

Fig. 18 shows in a similar section on line 18—18 55 of Fig. 1 the corresponding means for retracting

these clamping devices to release the boxes after they have been covered.

Before proceeding with the detailed description, attention is called to the fact that the paper or like boxes shown in position at the different stations of the illustrated machine are square ones in outline with sides of less height than length; and they are open at the tops toward the center of the machine. Each is covered laterally by a rectangular strip of somewhat greater width than the height of the sides so as to provide top and bottom marginal extensions which are folded over at the corners and adhesively secured to the box without cutting.

To facilitate an understanding of the related functions of the machine of this invention, a very general outline of operation will now be stated.

OUTLINE OF OPERATION

As the uncovered boxes are fed to the machine, they are in turn gripped securely by a clamping device, which is automatically expanded within each of them, and then moved stepwise through a circumferential series of stations for covering.

From the clamping station A, the box blank progresses to a wrapping station B where its circumferential movement is again suspended and it is turned approximately one and one-quarter times with its clamping device so as to wrap a length of adhesive coated paper completely around its four sides with a substantial overlap. After this wrapping, the paper is severed and the supply withdrawn; and the box then advances to the next station.

At this point, which will be termed a side and edge wiping station C, the projecting marginal portions of adhesive coated paper on opposite sides of the box are bent horizontally by yielding wiping members and the marginal portions adjacent the corresponding top edges are secured face-to-face to the inner surface of the box.

An end and edge wiping station D next receives the box, and wiper members there fold over and inturn the remaining opposite marginal portions in the same manner as at the preceding station.

Finally, the box advances to an unclamping station E where it is discharged from the machine and removed in any desirable way.

It will be understood that the instrumentalities at all stations are operated simultaneously when the boxes are stopped and that all box holding or clamping devices are rotated or advanced one step in unison after completion of each cycle of station operations.

Referring to the drawings, a spaced pair of vertical frames 20 and 22 (Figs. 1 and 2) connected by outwardly disposed transverse members, such as 24, horizontally support a rotatable shaft 26 to which are keyed five, uniformly spaced and identical, radial arms 28 through a central spider 29. These arms 28, which rotate in a vertical plane between the frames 20 and 22, each carries at its outer end, a box clamping device 30 engaging the inside corners of the boxes well below the edges defining the open side of each, as clearly shown in Fig. 4.

THE CLAMPING DEVICE

Figs. 3, 4, and 5 illustrate one of the clamping devices 30 which has four similar fingers or rods 32 extending at right angles to each other in the same general plane with an integral, vertical box-engaging strip 33 at its outer end, and preferably round in cross section. The fingers 32 are extended and retracted with respect to a common

center by a rotatable cam plate 34 having a curved slot 36 for each finger.

A four-armed spider formed by a pivoted crossed pair of interfitting arms 37 and 38 having a round rod 40 at the two ends of each arm carrying a sleeve 42 supports the fingers 32 reciprocably. The sleeve 42 is provided with a lug 44 slidably receiving one of the fingers 32 and having a set screw 46 for selectively adjusting the effective length of each finger. Each sleeve 42 is normally held in its outermost position by a suitably seated compression spring 48, and has a cam follower pin 50 projecting from its inner end and extending within one of the inwardly spiraled cam slots 36.

The fingers 32, as seen in Fig. 5, are predetermined in their extended positions in relation to the cam plate 34 by an underlying strip 52 secured to the spider arms 37 and 38 and having a longitudinal slot 54 at each end receiving a clamping screw 56 formed to provide a pivot for and retain the adjacent ends of a pair of tie strips 58 connected by their other respective ends to adjacent fingers 32, 32 by a pivot screw 60 also holding a stop collar 62 on the rod 40 abutting the sleeve 42 of each. The adjustment shown permits all of the cam follower pins 50 to reach the outer limits of the cam slots 36 to produce a right-angled relation of the fingers 32 for engagement with a square box. When the box is an oblong one, however, the angular relation of the diagonals represented by the aligned pairs of fingers 32 is manually changed by moving the commonly pivoted ends of tie strips 58 inwardly of their slots 54 and clamping them with screws 56 in the required positions. This will cause the corresponding adjacent pair of cam follower pins 50 to be moved equal distances inwardly of their cam slots 36, thus establishing different initial positions for full extension or clamping engagement. As shown in Fig. 3, spider arm 37 has an angular groove 63 for preventing complete overlapping with spider arm 38.

Each of the arms 28 carrying the clamping devices 30 comprises a hollow shaft 64 to the outer end of which the spider arms 37 and 38 are attached for relative rotating movement by means such as a screw 66, and with which the slotted strip 52 may be made integral.

The outer portion of shaft 64 rotatably supports a sleeve 68 concentrically and rigidly connected to the slotted cam plate 34 inwardly of strip 52.

Intermediate the length of shaft 64, the sleeve 68 has rigidly secured thereto in the manner indicated in Fig. 4, a large cam member 70, of star shape, which will be described further, and is held against inward movement on the shaft 64 by a collar 72 keyed to that shaft and formed to receive the free end of sleeve 68.

From the foregoing, it will be apparent that turning of sleeve 68 in response to rotation of cam member 70 will move slotted cam plate 34 relative to its follower pins 50 to retract or permit extension of the set of fingers 32 which hold the box.

MEANS FOR PRODUCING STEP-BY-STEP ROTATION OF MACHINE

Referring to Figs. 12 and 1, a rigid frame attachment 74 provides spaced bearing supports for a power take-off shaft 76 which is driven constantly by an attached pulley 78 when the machine is in operation. A conventional intermittent motion drive, such as a Geneva wheel 80.

keyed on the parallel shaft 26 carrying arms 28, and its cooperating single-toothed wheel 81, is designed to turn said shaft 26 one fifth of a revolution at a time, in response to rotation of power take-off shaft 76 with which it is coupled, and thus advance the five arms 28 and their boxes from station to station in steps.

STATION A OPERATION

As will be further explained, each clamping device 30 has discharged a covered box and has its fingers 32 in retracted position when approaching lowermost station A (Fig. 1). Any suitable form of conveying means 82 may be used to feed boxes to this station where they will be partially supported by an aligned triangular belt 84, as indicated by the box in dotted lines.

The triangular belt 84 is not driven, but merely provides an outwardly or downwardly yielding support for the box which forces it all the way onto the clamping device 30, and then permits it to move toward the next station after it has been fully clamped. This is accomplished by a spaced pair of loose pulleys 86 and 88 defining a conveyor run parallel to the box bottom, and an apex pulley 90 having a shaft 92 turning loosely and reciprocable in slot means 94 to give and take up slack in the parallel run. The pulleys for belt 84 are suitably carried by the front frame 20 in the manner shown, and the reciprocating apex pulley 90 may be made sufficiently heavy to produce the desired resistance to depression of the belt by a box, or other well-known biasing means may be employed.

A fixed stop 96 mounted on the machine frame and including a cam follower roller 98 (Fig. 17) is formed and arranged to engage the cam 70, which is four-lobed, and in response to relative motion of the clamping device 30 adjacent Station A, rotate the sleeve 68 and slotted cam 34 to extend the fingers 32 into box-clamping engagement. This engagement will then be maintained by the wedging action of the four cam slots 36 on pins 50.

STATION B OPERATION

The paper cover cutting mechanism

At the lower right of Fig. 2 is a supply magazine 100 for rolls P of covering paper. The roll P on the left is feeding vertically downward to a guide roller 102, whence a horizontal run of paper extends to a parallel guide roller 104 located toward the front of the machine, as viewed in Fig. 1, and thence upwardly and over a further guide roller 106 adjacent an adhesive-applying (or activating) cylinder 108. As indicated, the cylinder 108 is rotatably supported in a liquid reservoir 110 arranged so that the lower part of said cylinder will extend below the surface of the liquid adhesive.

After the paper leaves the adhesive applying cylinder 108, it is led beneath a still further guide roller 112, and then in a long vertical reach to a guide roller 114, over which it passes near the top of the machine; thence the paper is led rearwardly to a final guide roller 116.

A depending arm 118 carries at its lower end a cooperating pair of small feeding rollers 120 and 122 between which the free end of the paper supply passes downwardly in the manner shown by the dotted position of Fig. 2. The arm 118 is horizontally pivoted at the top of the machine a short distance rearward of the front side of the

box at Station B, and is laterally positioned to avoid interference with the paper, in the manner clearly shown in Fig. 1.

A similarly pivoted and outwardly disposed arm 124 supports in cantilever fashion at its lower extremity a small paper pressing roller 126 which lies in vertical alignment and immediately below the inner feeding roller 122 when both arms 118 and 124 are advanced against a box. Note is further made that the pair of rollers 120, 122 and the paper pressing roller 126 first act half-way down one side of the box of Fig. 2, and that they yield somewhat in their arcuate paths to accommodate counter-clockwise rotation thereof.

By means to be described, the clamping device 30 carrying a box is given one and one-quarter turns at Station B, and a length of paper covering corresponding to this peripheral measure and degree of overlapping is severed automatically from the paper supply in a manner which leaves a dangling end below the pair of feeding rollers 120, 122, according to the dotted position in Fig. 2.

The cycle of operations accomplishing this result comprises gravitational advance of the arm 118 and its pair of feeding rollers 120 and 122 to the side of the box to be covered; a shortly subsequent advance to the same point of the pressing roller 126 on arm 124 upon release to the action of a spring suspended weight 128 connected by a flexible line 130 to the upper part of said arm 124 after passing over a frame-mounted guide pulley 132; withdrawal to original position of the feeding rollers 120 and 122 with the paper web between them; severing of this paper web a definite distance below rollers 120, 122 by swinging of a knife edge 134 pivoted at one side of the paper path; and return of the knife edge 134 and of pressing roller 126 to inoperative position. All of these instrumentalities are actuated in timed relation by the continuously turning power take-off shaft 76 (Fig. 12) in a way which will now be detailed.

An upwardly extending shaft 136 is supported for rotation in the frame attachment 74, and carries a bevel gear 138 at its lower end in mesh with a bevel gear 140 of equal size keyed to the power take-off shaft 76. Near the top of the machine as seen in Figs. 1 and 12, the upwardly extending shaft 136 drives another pair of similar sized bevel gears 142, 144, the latter of which is keyed to a shaft 146 having a universal joint connection 148 at its right or upper end for driving a like shaft 150 rotatably supported in the frame of the machine outwardly of station C. A further universal joint 152 connects shaft 150 with a stub shaft 154 horizontally supported for rotation in an upstanding frame bracket 156.

Arm 124 is operated by means comprising a rectangular rod 158 sliding horizontally in bracket 156 and having at its other end a sliding pivot connection 160 to the upper part of said arm 124. Preferably rod 158 is round in cross-section at pivot connection 160 and has an adjustable stop 162 adjacent its end for adjusting the effective length of the rod 158 and pulling the arm 124 clockwise in Fig. 2. This latter motion is induced by a pin 164 rotating with driven shaft 154 and engaging a cam-shaped follower plate 166 extending vertically and rigidly joined to the reciprocating rod 158. Engagement of the pin 164, which is rotating counter-clockwise with the shaft 154, with the follower plate 166 will swing 75 the biased arm 124 away from the box and hold

it withdrawn until further rotation of the pin 164 releases it gradually.

A second rectangular rod 158 sliding without turning in frame bracket 156 parallel to rod 158 has a pivoting and sliding connection (not shown) similar to connection 160 with swinging arm 118, and is provided on its outer end with a cam-shaped follower plate 170, like follower plate 166. Follower plate 170 is reciprocated periodically by a second pin 172, also rotating counter-clockwise with shaft 154, and in a plane parallel to that defined by pin 164, in a predeterminedly out of phase relation to follower plate 166 controlling swinging movement of the pressing roller 126.

With reference to the knife-edge 134, it is noted that a detachable bracket 174 has formed thereon a rearwardly and downwardly inclined bearing journal 176 for receiving a crankshaft 178 to which the lower end of said knife-edge 174 is secured, as shown best in Fig. 2. A crank 180 on the forward end of shaft 178 is pivotally connected to an upwardly extending pitman rod 182 so as to provide a normally downwardly inclined lever for swinging the knife-edge 134. Rod 182 extends upwardly to driven shaft 154 and is provided with a pawl hook 184 which is arranged to be moved upwardly by periodic engagement with a step 186 on a circular cam 188 carried on the outermost end of shaft 154. This circular cam 188 is laterally enclosed by a pair of flanges 190 and 192 spaced a distance sufficient loosely to receive and guide the rod 182 with a small amount of lateral movement, as will be apparent from Fig. 1. A tension spring 194 is attached to pitman rod 182, below cam 188, to bias it downward and toward the frame bracket 156.

When the paper covering web is extended laterally between the Fig. 2 dotted position of feeding rollers 120, 122 and the pressing roller 126 positioned against a box, the circular cam 188 will lift pitman rod 182 to swing the knife-edge 134 inwardly and downwardly through the paper web, leaving a short length dangling from rollers 120, 122 for subsequent applying to a box by pressing roller 126.

After the knife-edge 134 has severed the paper web, it will be quickly returned to its inoperative vertical position by spring 194 and the restraint of flanges 190, 192 on the upper end of pitman rod 182.

Box ROTATING MEANS

Consideration will now be given to the means for intermittently connecting the arms 28, each of which carries a box clamping device 30, to the constantly driven shaft 26 for rotation of the clamped boxes in cooperation with the paper applying roller 126 at Station B, for example. Clutch means designated generally 196 connect the inner ends of shafts 64 to a vertical bevel gear 198 (Figs. 4 and 12) constantly driven from shaft 76. Referring to Fig. 12, power take-off shaft 76 carries a small sprocket gear 200, near its inner end, for driving a chain 202 running over a much larger sprocket gear 204 integral with the adjacent end of a hollow shaft 206 having the previously mentioned bevel gear 198 keyed to its other end. Hollow shaft 206 of the thus provided speed reduction drive turns freely on the countershaft 25, and through its bevel gear 193, drives five separate bevel pinion gears 208, one for each arm 28, turning freely on the spider 29 joining said arms.

Each clutch means 196 comprises a clutch

face 210 on the base of the bevel pinion gear 208 engageable by an opposed clutch face 212 on a sliding clutch collar 214 splined onto the shaft 64 which turns the clamping device 30. A collar 216 is secured to the same shaft 64 in spaced relation to clutch collar 214 to serve as a fixed abutment for a coiled compression spring 218 arranged to urge the clutch faces 210 and 212 into driving engagement.

Spider 29 has a plurality of integral, laterally offset arms 220 which extend radially and beyond each of the bevel pinion gears 208 to afford a pivotal support for a shifting yoke 222 slotted to receive a pin 224 projecting laterally of the sliding clutch collar 214. An inner sleeve 225 is used to secure clamping device 30 to spider 29, as shown. The unpivoted end of yoke 222 carries a cam follower in the form of a freely turning roller 226 having its axis at right angles to the path of the sliding collar 214.

By means of a notched cam disc 228 (Figs. 12, 13, 16) coaxial with shafts 26 and 206 maintained stationary by a bar 229 rigidly secured to frame 20, the clutch faces 210 and 212 of each clutch means 196 are periodically engaged to produce rotation of arm 28 when their roller 226 drops into shallow cam notch 230 or 231 of arcuate shape, spaced 144 degrees, or twice the spacing of the radial arm 28, and disposed at the rest positions of stations B and D respectively (Fig. 1). However, a diametrically opposed projecting pair of identical arcuate segments 232 and 234 mounted on the side of bevel gear 198 are also arranged to act upon rollers 226 to prevent their dropping into notch 230 or 231 at certain predetermined times, which will be more fully explained hereinafter.

STATION C OPERATION

Wiping mechanism

In connection with the operating means at station C, reference will be made to Figs. 6 to 11 in the following description.

The box supported on arm 28 in Fig. 6 will have an opposite pair of sides parallel with the planes of operation of opposed wiping and clamping devices 236 and 238. Device 236 rotates about a fixed but adjustable axis 240 and the other device 238 has similar but opposite movement about a fixed axis 242. The axis 240 is defined by a spaced pair of depending bracket supports 244, 244 (Fig. 7) joined by a horizontal slide frame 246 supported by a spaced pair of track rods 248 and 250 (Fig. 8). As indicated, the slide frame 246 and pivot axis 240 may be adjusted along the track rods 248 and 250 and maintained in adjustment by clamping screws 252.

On the other end of the box, a similar pair of bracket supports 254, 254 are provided for the device 238 and are connected by a horizontal slide frame 256 also provided with clamping screws 258 for use in adjusting the position of pivot axis 242.

The wiping and clamping devices 236 and 238 are swung and operated about their respective axes 240 and 242 by means of individual reciprocating operating rods 260 and 262 supported in the frame members 20 and 22 to which the track rods 248 and 250 are shown as secured.

An adjustable cross bar 264 for device 236 is secured adjustably to operating rod 260 by means of a clamping screw 266, and a similar cross bar 268 for device 238 is clamped to operating rod

262 by a screw 270. At opposite ends of cross bar 268 and beyond the extremities of the box, a pair of operating links 272 and 274 are pivoted. Link 272 is pivotally connected at its other end with a crank plate 276 forming a permanently pivoted part of device 236. It will be noted that the device 238 at the opposite end of the box includes a similar crank plate 278 connected by an additional link 280 extending parallel to an identical link 282, both of these links being pivotally connected at their distant ends to the extremities of cross bar 264.

The wiping and clamping device 236 acts with an identical companion device 284 at the opposite end of the same side of the box and connected to the adjacent end of link 274. In like manner, the device 238 is provided with an identical companion device 286 with pivotal connection to operating link 282.

Referring to Figs. 6 and 7, the frame supported shaft 150, which is driven directly and continuously from the power take-off shaft 76, carries a drive sprocket 288 with a chain 290 arranged to drive a similar sprocket 292 on a parallel countershaft 294. The shaft 294 is rotatably supported by and between a spaced parallel pair of U-shaped supports and guides 296 and 298, the first for the reciprocable operating rod 260 and the second for the other operating rod 262. The means for producing reciprocating motion of rod 260, operating clamping devices 236 and 238 comprises a circular plate 300 on shaft 294 which plate carries a projecting crank pin 302 engaging a vertical slide plate 303 in support 296. As shown best in Fig. 6, the slide plate 303 has a cam groove 304 receiving the crank pin 302. The other support 298 for the operating rod 262 which actuates clamping devices 236 and 284 is provided with a vertical plate 306 similar in all respects to plate 303 and cooperating with a second circular plate 308 on shaft 294 through the means of a crank pin 310. While the cam plates 303 and 306 are alike, it is to be noted that they are always oppositely moving, as required for the proper operation of the swinging devices at both ends of the box, and that their respective crank pins 302 and 310 are consequently 180 degrees out of phase.

Consideration will next be given to the details of one of the four wiping and clamping devices, all of which are similar in construction and operation. The device 236 comprises a vertical swinging base plate 312 which has limited rotation in two directions about the pivot axis 240. The crank plate 276 referred to previously is pivoted and secured at an intermediate part, by means of a pin 314 carried by the base plate 312. Adjacent the box edge of base plate 312 is a smaller vertically sliding plate 316 having an upper guide slot 318 and a lower guide slot 320 cooperating with a vertically spaced pair of guiding and retaining pins 322 and 324 on the adjacent face of base plate 312. The slide plate 316 has an outwardly extending apertured lug 326 forming a loop for sliding and lifting connection with a reduced end 328 on the shorter arm of crank plate 276 (Fig. 9). The movement of crank plate 276 is controlled and restrained by an arcuate guide slot 330 concentric with pivot pin 314 and engaged by a guide pin 332 mounted on base plate 312.

The companion pairs of clamping devices 236—284 and 238—286 have their base plates 312 connected together by a transverse plate element 334 formed and arranged to engage the adjacent

side face of a box throughout its entire area and carrying an upper resilient wiper 336 along its uppermost portion. As shown in Figs. 8, 9 and 10, the upper wiper 336 is formed by a uniformly and closely spaced series of parallel U-shaped spring loops 338 defining a flat lower surface for laying the upper projecting edge of the cover paper on the bottom of the box.

A lower resilient wiper 340 is formed by a rigid horizontal bar 342 which extends between and connects the lower ends of companion pairs of vertically sliding plates 316 and supports a series of vertically extending U-shaped spring loops 344. As in the case of upper wiper 336, the loops 344 are parallel and uniformly and closely spaced.

It is the function of the lower resilient wiper to turn the downwardly extending edge of the box cover inwardly and upwardly so as to fold it and lay it over the top edge of the box and along the inner surface immediately below that edge. The flexible nature and close spacing of the spring loops 344 make it possible for a wiper of given length to accommodate itself automatically to boxes of various dimensions by the simple expedient of fitting either within or without the box at its extremities, and yielding to either one side or the other without damage to the box.

As each pair of wiping and clamping devices is swung toward a box about their parallel horizontal axes 240 and 242 respectively, they will first attain a perpendicular position against the opposite sides of the box and the upper and lower extending marginal portions of the cover will be wiped into the horizontal positions indicated in Fig. 10 by the respective wipers. Continued movement of the crank plates 276 after the base plates 312 can advance no further, will cause the ends 328 of those plates to lift the slide plates 316 vertically and relative to the base plate 312 so that the lower resilient wiper 340 will further fold the lower edge extension of the cover and lay it against the inner surface of the box, as plainly shown in Fig. 9. Note is made that this final movement of lower wiper 340 is also relative to the upper wiper 336 carried by transverse plate element 334. Withdrawal of the wiper elements and then of the clamping devices from the box proceeds in exactly reverse order.

STATION D OPERATION

Wiping mechanism

When a box reaches station D (Fig. 1), it is first given a quarter turn by rotation of its supporting arm 28 and by means of a universal joint connection 345 to shaft 146, a frame supported shaft 346, similar to shaft 150, turned to operate a sprocket drive 347 identical with that at Station C. The sprocket drive 347 operates a wiping and clamping means 348, just described, for station C, and serving to fold and lay the remaining projecting edges of the box cover on opposite sides thereof.

STATION E OPERATION

After a box leaves station D, its clamping device will be released by engagement of one arm of the cam member 70 with a fixed stop 350 having a cam follower roller 352 (Fig. 18). It is necessary that the cam 70 have four equally spaced lobes, as shown, in order that one will always be in proper position for engagement with roller 352 after the box has been given a total of one and one-half turns at the preceding stations. The box will be completely covered and disengaged so

that it can fall from the clamping device 30 when it stops at station E.

TIMING OF OPERATIONS

The timing of the rotation of the arms, the turning of the box clamping devices 30 at certain stations, and the cooperative operating mechanisms located at some of the stations represents a very important aspect of the invention, being essential to the full automatic functioning of the machine. Figs. 1 and 12 to 16 will be referred to in explaining the means for achieving the required synchronism and coordination.

Driven directly by continuously turning power pulley 18, the toothed wheel 81 turns the five-slotted Geneva wheel 80 intermittently one-fifth of a turn for every complete turn of said pulley 18. This movement, through shaft 26, advances the clamping devices 30 and their supported boxes from station-to-station. During the remaining four-fifths of a turn of power pulley, the Geneva wheel 80 remains stationary and the respective station operating mechanisms are actuated by the driven shaft 146 which turns at the same speed as pulley 18.

The eighty-tooth bevel gear 198 which turns the twenty-tooth clutch pinions 208 of the individual arms 28 is driven at one-third the speed of pulley 18 through the sprockets 200 and 204.

At station B, while the arms 28 are stationary, pinion 208 is given one and one-quarter turns by one of the twenty-five tooth segments of bevel gear 198 (Fig. 15), while the corresponding clutch means 196 is in driving engagement with arm 28 due to the position of clutch roller 226 in arcuate notch 230. This movement of arm 28, which is also imparted to a box on clamping device 30, is concurrent with the operation of the paper applying roller 126 and subsequently knife-edge 134; the latter two instrumentalities complete the operative part of their cycle during the dwell of the arms 28 at the various stations.

At station D, the only other where the box-carrying arms 28 are turned, each of said arms is given one-quarter turn immediately upon arrival, to permit folding and in turning of the remaining opposite side paper cover portions not manipulated at station C. This turning of the box must be accomplished before the pivoted wiping assemblies 236, 238 have closed together far enough to interfere with turning. The availability of five teeth of bevel gear 198 before clutch roller 226 is removed from the stationary notch 231 by cam segment 232 on the under face of this gear produces the required turning of arm 28 at station D.

As previously indicated, the operating mechanisms at stations B, C, and D go through their cycles continuously, the cycle of each starts at the same time (when the arms 28 stop their rotation about the axis of shaft 26), and the respective cycles are in the dwell or idle phase when the arms 28 and their boxes are advanced from to successive stations.

Obviously, certain components of the machine of this invention, such as the clamping device and wiping or folding, possess utility in other combinations, and for this reason have been claimed separately as sub-combinations. It is also to be recognized that the broad principles of this invention can be embodied in a variety of forms of mechanism other than that illustratively disclosed, and that the invention is not to be limited to any specific construction and arrangement of parts, except as may be required by the spirit and scope of the appended claims.

Having thus described my invention, what I claim as new and desire to secure by Letters Patent of the United States is:

1. A box covering machine comprising a plurality of angularly spaced box supporting arms rotatable together about a common axis, means for turning said arms at certain positions in their path of rotation while stationary, means for supplying covering paper to a box while its arm is turning at one of said positions, means for cutting the covering paper thus supplied after the said arm has turned a predetermined amount and means operable on different sizes of boxes for inwardly folding upwardly and downwardly extending marginal portions of the paper box covering at a succeeding position, said folding means comprising a bar supporting a row of elements widely spaced relative to their width, said elements being adapted to receive opposite edge portions of a box therebetween.
2. A box covering machine comprising a plurality of angularly spaced box supporting arms rotatable together about a common axis, means for rotating said arms intermittently about said axis, means for turning said arms at certain positions in their path of rotation while stationary, means for applying covering paper to the sides of a box while its arm is turning at one of said positions, means for cutting the covering paper thus supplied after the said arm has turned a predetermined amount and means operable on different sizes of boxes for inwardly folding upwardly and downwardly extending marginal portions of the paper box covering at a succeeding position, said folding means comprising a bar supporting a row of elements widely spaced relative to their width, said elements being adapted to receive opposite edge portions of a box therebetween.
3. A box covering machine comprising five arms connected together and equally spaced angularly, a box clamping device at the outer end of each arm, means for rotating said arms stepwise about a horizontal axis, means for turning said arms and clamping devices at certain positions while at rest, means for applying a continuous paper supply to a clamped box at one of said positions, paper cutting means at said last-mentioned position operable when the box has been partly covered, means for wiping down extending marginal portions of the paper box covering at a succeeding position, and means for wiping down other extending portions of said covering at a further succeeding position, said wiping down means being constructed and arranged to operate on different sized boxes and comprising a bar having thereon a row of elements widely spaced relative to their width, said elements being adapted to receive opposite edge portions of a box therebetween.
4. A box covering machine comprising a plurality of arms connected together and equally spaced angularly, a box clamping device constructed and arranged to engage the inside of a box and mounted at the outer end of each arm, means for rotating said arms stepwise about a fixed axis, means for turning said arms and clamping devices at certain positions while at rest, means for applying a continuous paper supply to the sides of a clamped box at one of said positions, paper cutting means at said last-mentioned position operable when the box has been partly covered, and means for inwardly folding upwardly and downwardly extending marginal portions of the paper box covering at a succeeding position, said folding means being constructed

and arranged to operate on different sized boxes and comprising a bar supporting a row of elements widely spaced relative to their width, said elements being adapted to receive opposite edge portions of a box therebetween.

5. A box covering machine comprising five arms connected together and equally spaced angularly, an expansible box clamping device constructed and arranged to engage the inside of a box and mounted at the outer end of each arm, means for rotating said arms stepwise about a horizontal axis, means for turning said arms and clamping devices at certain positions while at rest, means for applying a continuous paper supply to the sides of a clamped box at one of said positions, paper severing means at said last-mentioned position operable when the box has been partly covered, means for wiping down extending marginal portions of the paper box covering at a succeeding position, means for wiping down other extending portions of said covering at a further succeeding position, and means for giving each arm and clamping device a partial turn at said further succeeding station and before operation of the wiping down means said wiping down means being constructed and arranged to operate on different sized boxes and comprising a bar having thereon a row of elements widely spaced relative to their width, said elements being adapted to receive opposite edge portions of a box therebetween.

6. A box covering machine comprising a spaced pair of vertically extending frame members, five arms connected together and equally spaced angularly, an expansible box clamping device constructed and arranged to engage the inside of a box and mounted at the outer end of each arm, means for rotating said arms stepwise about a horizontal axis supported between said frame members, means for turning said arms and clamping devices at certain positions while at rest, means for applying a continuous paper supply to the sides of a clamped box at one of said positions, paper severing means at said last-mentioned position operable when the box has been partly covered, means for wiping down extending marginal portions of the paper box covering at a succeeding position, means for wiping down other extending portions of said covering at a further succeeding position, means for giving each arm and clamping device a partial turn at said further succeeding station and before operation of the wiping down means, said paper applying means, paper severing means, and paper wiping means being operable on different sized boxes and supported by said frame members outwardly of the arms, and means for operating each clamping device in turn as it rotates with its arm, said wiping means comprising a bar supporting a row of elements widely spaced relative to their width, said elements being adapted to receive opposite edge portions of a box therebetween.

7. In a box covering machine, supporting means formed and arranged to engage the inside of a box, and means for folding and laying the projecting edge of a paper covering wrapped around the box, said folding and laying means including a resilient wiper formed of a plurality of elements spaced widely apart relative to their width and adapted to receive opposite edge portions of different sized boxes therebetween.

8. In a box covering machine, supporting means formed and arranged to engage the inside of a box, and means for folding and laying the

projecting upper and lower marginal edge portions of a paper covering applied to a side of the box, said folding and laying means including a pair of relatively movable resilient wipers formed of a plurality of elements spaced widely apart relative to their width and adapted to receive opposite edge portions of different sized boxes therebetween.

9. In a box covering machine, supporting means formed and arranged to engage the inside corners of an open rectangular box beyond its open edge, and means for folding and laying the projecting marginal edge portion of a paper covering adhesively applied around the sides of the box, said folding and laying means including a resilient wiper formed of a plurality of spaced spring elements of loop shape for operation on different sized boxes, certain of said spring elements receiving opposite edge portions of a box therebetween and all of said spring elements lying in parallel planes perpendicular to the surface to be wiped and parallel to the ends of the box not to be wiped and being widely spaced relative to their width.

10. A resilient wiper for a box covering machine comprising, a bar, and a plurality of uniformly spaced wire loops secured to said bar, for receiving opposite edge portions of different sized boxes therebetween, said loops lying in parallel planes perpendicular to the surface to be wiped and parallel to the ends of the box not to be wiped and being widely spaced relative to their width.

11. A resilient wiper for a paper box covering machine comprising, a bar, and a plurality of spaced wire loops of U-shape secured to said bar in parallelism to lightly press against the edge portions of a box, and to receive other opposite edge portions of different sized boxes therebetween, said loops being perpendicular to the surface to be wiped and parallel to the ends of the box not to be wiped and being widely spaced relative to their width.

12. A wiper for a paper box covering machine comprising, a bar, and a plurality of uniformly spaced resilient loops secured to said bar in parallel relation and perpendicular to said bar, said loops being adapted to receive opposite edge portions of different sized boxes therebetween, and said bar being parallel to the surface to be wiped and perpendicular to the ends of the box not being wiped, said loops being widely spaced relative to their width.

13. In a paper box covering machine of the character described, a wiper comprising a series of spaced and parallel resilient elements, and means for moving the elements of said wiper transversely across an edge of a box, said elements being widely spaced relative to their width and adapted to receive opposite edge portions of different sized boxes therebetween.

14. In a paper box covering machine of the character described, a resilient wiper comprising a bar and a plurality of spaced wire loops, and means for moving said wiper parallel to the plane of a loop and horizontally across an edge of a box and then vertically upward to insert certain of said wiper loops within said box edge and against the inside of said box, whereby an extending marginal portion of covering paper is folded inwardly and laid on the inside surface of the box, said wire loops being widely spaced relative to their width and adapted to receive opposite edge portions of different sized boxes therebetween.

WILLIAM B. BETTS.
